(57) **CLAIM**

The ornamental design for a modular tool storage drawer, as shown and described.

DESCRIPTION

FIG. 1 is a perspective upper view of the modular tool storage drawer with tools inside shown in dotted lines;
FIG. 2 is a perspective view of an empty modular tool storage drawing showing the front and left side, the right side of the drawer corresponding to the left side view;
FIG. 3 is a rear view thereof;
FIG. 4 is an exploded view thereof; and,
FIG. 5 is a perspective view of three modular tool storage drawers in combination with tools shown in dotted lines. The dotted line depiction of the tools in FIG. 1 and FIG. 5 is not part of my design.
